MERCURY ARC DEVICE

Leonard M. Wittlinger, Flint, Mich., assignor to
 General Motors Corporation, Detroit, Mich., a
 corporation of Delaware

Application September 27, 1943, Serial No. 503,879

10 Claims. (Cl. 315—56)

1

This invention relates to lighting means and more specifically to means for producing ultraviolet rays.

There are many instances in which ultraviolet rays are useful or necessary for various lighting problems and in many of these sources of high voltage may not be readily obtainable. As an example of this, signaling or lighting under combat conditions make it necessary that no more than absolutely essential light be used for these purposes which might be discernible by an enemy. In moving vehicles at night under black-out conditions, it has been found that by using some type of luminescent or fluorescent paint, objects along a path painted therewith can be discerned by projecting thereagainst ultraviolet rays to fluoresce the same and indicate a course or path of the objects. In such vehicles, of course, the usual source of power is a storage battery or small generator having in the neighborhood of six or twelve volts. This, of course, is insufficient to draw an arc in an ordinary mercury tube, but there have been developed previously such devices as shown in Brian Patent 2,289,623 having one portion of the device operating on low voltage to provide an interrupted current and a second portion operating on higher voltage to provide an arc section and therefore a source of ultraviolet rays.

However, in these instances the upper or high potential electrode forming one end of the arc gap is intended to be an anode and cooperate with the mercury pool as cathode, but under certain circumstances a reversal of polarity is obtained, making the upper electrode a cathode and causing it to erode or sputter and parts thereof to contact the inner surface of the surrounding tube and both blacken the same and cause the electrode to wear away.

It is therefore an object of my invention to provide means for preventing sputtering or eroding of an electrode of a mercury arc device.

It is a further object of my invention to provide means to maintain the upper arc electrode at a positive potential with respect to the mercury electrode.

It is a still further object of my invention to provide means for maintaining a constant polarity on one of the electrodes of a mercury arc device.

With these and other objects in view which will become apparent as the specification proceeds, the embodiments of my invention will be best understood by reference to the following

2

specification and claims and the illustrations in the accompanying drawing, in which:

Figure 1 is a vertical section through a mercury arc tube showing the external circuit connections embodying one form of my invention.

Figures 2 and 3 are views similar to that of Figure 1, showing modified forms embodying my invention.

Referring now more specifically to the disclosure of Figure 1, there is shown therein a tube or envelope 2 housing a body of mercury 4 in its lower portion and having sealed into the bottom thereof an electrode 6 which is staked into a small carbon disc 8 surrounded by a ceramic disc 10. A second electrode 12 is supported in the side of the envelope and forms with the carbon electrode 8 the interrupter section of the tube. Supported in the upper end of the tube 2 are two spaced electrodes 14 and 16 which project into the interior of the tube but are spaced from the upper surface of the mercury pool 4. The exterior electrical circuit includes a line 18 which connects electrode 6 with one side of a primary 20 of a transformer, the opposite side of the primary being connected through line 22 with a positive side or battery 24, the negative pole of the latter being connected through line 26 with electrode 12. The secondary 28 of the transformer has one terminal connected through line 30 to electrode 14 and the opposite side connected through line 32 to electrode 16. A pair of condensers 34 and 34' are connected in series across between these lines and a center tap on the secondary 28 is connected through line 36 to ground 38 and to a point between the two condensers.

In the operation of this form of my invention, an obvious series circuit is provided between the battery, transformer primary 20, electrodes 6, 8, mercury 4 and electrode 12. When current flows in this circuit, the mercury in contact with the upper surface of the carbon 8 heats the same sufficiently to cause it to vaporize and flash off this surface. This causes the circuit to be broken inasmuch as the voltage is insufficient to sustain a mercury arc through vapor at this point. The mercury therefore recondenses and the circuit is reformed to allow current to again flow. Thus an intermittent interruption of the current flowing through the primary coil 20 is obtained. Therefore as the current in primary 20 is allowed to flow and is interrupted periodically, current will be induced in the secondary 28 in a ratio dependent upon the ratio of the turns of the coils and a relatively high voltage will be alternately applied first to electrode 14 and then to electrode

16, dependent upon the direction of flow of current, but always one or the other of these two electrodes will be at a positive potential with respect to the mercury 4. Thus there can be no reversal of polarity and the electrodes 14 and 16 cannot become cathodes and the above identified defects will be cured.

Figure 2 shows another form of my invention in which the tube 2 is exactly the same as that shown in Figure 1 but the external circuit varies. The tube as before has two high potential electrodes 16 and 14 in the upper portion and the interrupter electrodes 12 and 6, the latter being connected to the carbon disc 8 in contact with the mercury pool 4. In this case also the lower electrode 6 is connected through line 18 with transformer primary 20' and thence through line 22 to the positive pole of the battery 24, the negative pole, as previously, being connected through line 26 to electrode 12. The transformer secondary 28' in this case, however, has one side connected through line 40 to rectifier electrode 42 of a double half wave rectifier tube 44, the cooperating rectifier electrode 46 of which is connected through line 48 with tube electrode 16. In like manner the opposite side of the secondary 28' is connected through line 50 with a further rectifier electrode 52, the cooperating electrode 54 of which is connected through line 56 with the tube electrode 14. The center tap of the transformer is connected through line 58 with line 26, condenser 60 and condenser 62. Thus this form of my invention incorporates a positive rectifier between the output of the secondary of the transformer and the two high tension electrodes 14 and 16. The operation is the same generally as in the previous instance, the electrodes 14 and 16 alternately becoming the positive electrode with respect to the mercury meniscus to provide the arc.

In Figure 3 there is shown a different style of tube and in this instance the tube envelope 2' has a pool of mercury 4' therein and the lower or base portion of the tube supports an electrode 12' in spaced relation to a second electrode 6'. This latter electrode 6' is staked into a vertical carbon electrode 64 which in this instance is sealed by an insulating sleeve 66 leaving only an angular upper surface 68 exposed to the mercury. This provides the interrupter section of the tube. The upper portion of the tube is evacuated and the upper end supports an arc electrode 70. The electrode 6' is connected by line 72 to the positive pole of the battery 24, the negative pole of which is connected through line 74 with one terminal of the primary transformer winding 20'', the other terminal of which is connected by line 76 to tube electrode 12''. The secondary winding 28'' has one terminal connected through line 78 to condenser 80, the opposite side of which is connected directly by the line 82 with one electrode 84 of a rectifier tube 86. The other rectifier electrode 88 is connected through line 90 with the other side of the secondary 28''. A condenser 92 is connected directly across the secondary 28'' and line 78 is connected to a line 94 which extends to line 72 connected to the positive pole of the battery. Line 82 is also connected to conductive line 96 which extends to the arc electrode 70. In this instance, as in the previous case, the interrupter electrodes 6', 64, 4' and 12' provide a periodic pulsating current in the primary 20'' of the transformer. This induces a similar current of higher voltage in the secondary 28'' which current is rectified by the tube 86 and applied to the electrode 70 to maintain the same always positive

with respect to the mercury and therefore prevent reversals of the voltage within the tube to cause deterioration and darkening of the surface.

I claim:

1. In a light source for ultraviolet rays, a transparent casing, a pool of mercury partially filling said casing, a plurality of electrodes of dissimilar materials mounted in the casing and contacting the mercury, a low voltage source of power connected to said electrodes to form therewith an interrupter, a transformer in the low voltage circuit, a high voltage circuit connected to the transformer, further electrode means mounted in the casing spaced from the mercury and connected to the high voltage circuit to cause an arc to form between the last-named electrode means and the mercury and means in the high voltage circuit to maintain a given arc polarity of the mercury and last-named electrode means.

2. In a light source for ultraviolet rays, a transparent casing, a pool of mercury partially filling said casing, a plurality of electrodes of dissimilar materials mounted in the casing and contacting the mercury, a low voltage source of power connected to said electrodes to form therewith an interrupter, a transformer in the low voltage circuit, a high voltage circuit connected to the transformer, further arc electrode means mounted in the casing spaced from the mercury and connected to the high voltage circuit to cause an arc to form between the last-named electrode means and the mercury, and rectifier means in the high voltage circuit to maintain the arc electrode means at a positive potential with respect to the mercury pool.

3. In a light source for ultraviolet rays, a tube partially filled with mercury having an interrupter section and an arc section, a low voltage source of power connected to the interrupter section, a transformer having a high and low potential winding, the latter being connected into the low voltage circuit, a high voltage circuit connecting the high voltage winding with the arc section and means to maintain the arc section of constant polarity during its operation.

4. In a light source for ultraviolet rays, a tube partially filled with mercury, a plurality of electrodes carried by the tube, some of which are immersed in the mercury and some spaced therefrom, low voltage means connected to the immersed electrodes and forming therewith an interrupter, and means for alternately applying a higher potential than that of the mercury to the spaced electrodes to draw an arc from the mercury meniscus maintaining the latter as a cathode.

5. In a light source for ultraviolet rays, a tube partially filled with mercury, a plurality of electrodes carried by the tube, some of which are immersed in the mercury and some spaced therefrom, low voltage means connected to the immersed electrodes and forming therewith an interrupter, transformer means connected to the low voltage circuit and to the spaced electrodes to apply high voltage thereto to create an arc between them and the mercury meniscus.

6. In a light source for ultraviolet rays, a tube partially filled with mercury, a plurality of electrodes carried by the tube, some of which are immersed in the mercury and some spaced therefrom, low voltage means connected to the immersed electrodes and forming therewith an interrupter, transformer means having primary and secondary circuits, the primary being con-

nected to the low voltage circuit and the secondary to the spaced electrodes to apply high voltage thereto to create an arc between them and the mercury meniscus, and rectifier means in the high voltage circuit to maintain the spaced electrodes positive with respect to the mercury.

7. In a light source for ultraviolet rays, a tube partially filled with mercury, a plurality of electrodes carried by the tube, some of which are immersed in the mercury and some spaced therefrom, low voltage means connected to the immersed electrodes and forming therewith an interrupter, transformer means comprising primary and secondary windings, the primary being connected to the low voltage circuit and the secondary to the spaced electrodes to apply high voltage thereto to create an arc between them and the mercury meniscus, and means for grounding the center of the transformer secondary.

8. In a light source, a casing, conductive means between which an arc may be created supported in spaced relation by said casing, a primary circuit having fluctuating current flowing therein, a secondary circuit coupled thereto and interconnecting said primary circuit; and said conductive

means and means in said secondary circuit to maintain the polarity of said conductive means the same at all times during energization.

9. In a light source, a transparent casing, a pool of electrically conductive fluid in said casing, electrode means mounted in the casing spaced from the surface of the fluid, a primary circuit having fluctuating current flowing therein, a secondary circuit coupled thereto and interconnecting said electrode means and the fluid to cause an arc to form therebetween and means in the secondary circuit to maintain the electrode means at the same polarity with respect to the fluid at all times during operation.

10. In a light source, a transparent casing, a pool of mercury partially filling said casing, electrode means mounted in said casing spaced from the surface of the mercury, a primary circuit having fluctuating current flowing therein, a secondary circuit coupled thereto and interconnecting said electrode means and said mercury to cause an arc to form therebetween and means in the secondary circuit to maintain the electrode means at a positive potential with respect to the mercury at all times.
